Geo. A. Wheelock

UNITED STATES PATENT OFFICE.

HARRIS LEVIN, OF FREEPORT, NEW YORK.

METHOD OF PRODUCING FINGER-RING GUARDS.

Application filed March 26, 1928. Serial No. 264,820.

The present invention relates to a novel method of producing novel finger ring guards. In my prior U. S. Letters Patent No. 1,341,218, a ring guard is disclosed which is composed of four pieces of metal, the end members being made from soft metal, whereas the side members are made of harder metal, the four pieces being soldered together at four places, thus making the operations expensive and undesirable on account of breaking of the joints formed by the solder. Under the method of the present invention practical ring guards are produced which do away with the necessity of soldering and considerable filing, by making each of them of one piece of sheet metal, preferably 14 carat gold, and wherein the end jaw members are softer than the side members which are springy so as to hold the guard on the ring.

Other objects of the invention are to provide a method whereby a practical ring guard is produced in which the soft end members are thinner and wider than the side members, in order to be able to readily cause the end jaw members to encircle the ring snugly and to remain so, and wherein the entire guard is smooth and presents no sharp edges anywhere which will come in contact with the finger or damage fabric material.

These being among the objects of the present invention, the same consists of certain novel method steps to be hereinafter described and then claimed with reference to the accompanying drawings which illustrate desirable embodiments of the invention and wherein:

Figure 1 is a plan of a metal blank in the preferred loop form;

Fig. 2 is a sectional detail of the male and female dies which are preferably used in the first step of forming up the blank;

Fig. 3 is a transverse section on the line 3—3, Fig. 2;

Fig. 4 is a plan of the female die;

Fig. 5 is a plan of the blank after it has been subjected to the action of the said dies;

Fig. 6 is a sectional elevation showing an apertured plate through which a plunger is adapted to force the formed blank of Fig. 5 to bend it longitudinally;

Fig. 7 is a transverse section, partly in elevation, showing the plunger before it strikes the formed blank, the latter being held in the apertured plate before being operated on by the plunger;

Fig. 8 is a transverse section on the line 8—8, Fig. 6;

Fig. 9 is a plan of the said apertured plate;

Fig. 10 is a sectional elevation showing means for finishing the end jaw members 60 of the guard, while the latter is still in a formative state;

Fig. 11 is a transverse section on the line 11—11, Fig. 10;

Fig. 12 is a sectional elevation illustrating 65 dies for bending and hardening the side members of the ultimate ring guard;

Fig. 13 illustrates a finger ring with the improved ring guard applied thereto, and

Fig. 14 is an enlarged section on the line 70 14—14 of Fig. 13.

Referring to Fig. 1, a loop shaped metal blank is illustrated which comprises side members 15, 16 and end members 17 and 18 and the first step of the method may include 75 the forming of such a blank from a sheet of suitable metal such as 14 carat gold. It will be observed that the side members 15, 16 are curved inwardly toward each other and that the end members 17, 18 are curved outwardly, the members 15, 16 being similar to each other and the members 17, 18 being similar to each other. The four side and end members of the soft sheet metal blank lie substantially in one plane.

Referring to Figs. 2, 3 and 4, suitable dies are shown for subjecting parts of the soft sheet metal blank to pressure so as to partly deform the blank. A female die 19 is provided with an impression or grooves 20, 21, 22, and 23 formed to the general shape of the blank shown in Fig. 1. The side portions 20, 21 of the impression are formed substantially to the outlines of the side members 15, 16 of the blanks, while the end portions 80 22, 23 of the impression are curved longitudinally thereof, as shown in Fig. 3, said end portions 22, 23 being rather wider than the end members 17, 18 of the blank. The male die 24 is provided with transverse 90 forming ribs 25 which are slightly less in dimension transversely than at the portions where they enter the impression portions 22, 23 of the female die. There are no corresponding compression ribs on the die 24, between the ribs 25, because it is not desired in this step of the method to act directly upon the metal of the side members 15, 16 of the blank.

The blank of Fig. 1 is placed in the impres- 110

105

sion of the female die 19 and pressure of suitable power is brought to bear on the male die 24, whereby the end members 17, 18 of the blank are slightly reduced in thickness and 5 the metal thereof is caused to flow while cold so as to conform to the width of the portions 22, 23 of the impression in the female die. At the same time the end members 17, 18 are slightly curved longitudinally while at the 10 points 26 the impression in the female die and the adjacent surfaces of the ribs 25 are slightly slanted upwardly, whereby to slightly turn up the ends of the end members 17, 18, with the result that the slightly bowed end members 17, 18 are somewhat out of the plane of the side members 15, 16. This fact in this 15 step of the method is disclosed in dotted lines, Fig. 2.

The step of stamping the end members, as 20 just described, results in more or less hardening of the metal thereof. Hence after this step in the method, the blank is annealed so as to again soften the end members, and they are left substantially in such soft condition 25 preferably throughout the entire method.

The action of the dies just described results in a formed blank such as shown in Fig. 5, wherein at the sides of the outer corners of the blank slightly turned up portions 30 26^a are formed, the end members 17, 18 being slightly bowed, as before stated.

The next step in the method is illustrated in Figs. 6, 7, 8 and 9. For this step a plate 27 is provided which has a longitudinal recess 28 and a longitudinal aperture 29. The recess 28 conforms substantially to the outlines of the thus formed blank, so as to furnish a seat for receiving the same for being subjected to the action of a plunger 30 which is provided with a bending head 31. The longitudinal aperture 29 in plate 27 is of slightly greater dimensions than the plunger head 31.

In this step of the method, the blank as 45 previously formed is placed within the plate recess 28, with the bowed end members 17, 18 so disposed that they bow in the direction in which the plunger 30 descends, as shown in Fig. 7. The plunger is then caused to descend so that its head 31 may easily act upon the end members 17, 18 of the blank so as to 50 curve and form them into the shape shown in Figs. 6 and 8, wherein the plunger has driven the entire partially formed ring guard through the longitudinal aperture 29 in plate 27. This step in the method forms the end members out of the blank into open jaws 32 and slightly turns inwardly the ends of the jaws at 33 as clearly illustrated in Fig. 8 preliminarily to the next step in the method.

60 The partially completed ring guard may be readily stripped off from the plunger head 31 by a longitudinal movement.

The next step in the method is shown in Figs. 10 and 11, wherein means are disclosed 65 for imparting final formation to the end

jaws. These views do not illustrate the complete thus formed up blank for the ultimate ring guard which comprises side members 34, 34^a and end jaw members 35, 35^a, such being illustrated in Figs. 12 and 14. However, 70 these Figs. 10 and 11 illustrate one of the side members 34, a partially formed jaw member 32 as formed in the previous step of the method, and a completely finished jaw member 35, which has just been formed according 75 to said figures. In these views a die block 36 is provided with a downwardly tapering hole 37 to one side of which is a tongue 38 which projects thereinto longitudinally thereof. A punch 39 is provided with a 80 punching or forming member 40, and the cross-sections of the hole 37 and the forming member 40 conform respectively to the contours of the outside and the inside of each 85 jaw member of the ultimately formed ring guard. These cross-sections are such that when a partially formed jaw member is inserted into the hole 37, with the tongue 38 entered in the unclosed gap at the ends of the 90 jaw member, and the punch driven down into the hole, the partially turned over portions 33 of the formed blank (Fig. 8) will be flattened, as shown in Fig. 11, and the final shape imparted to the jaw member, so as to finish 95 that member. When this has been done, the punch 39 is withdrawn and the so formed guard withdrawn from the die 36 and the partially formed jaw member 32 is then inserted within the hole 37 in the same manner 100 as before described. The punch is then caused to enter the aperture 37 so as to finally form up and finish this second jaw member, and the guard is then withdrawn from the die, the jaws being then in finished condition. In order to abut the edge of the partially 105 formed jaw member and to drive the latter snugly down into the hole 37, the punch 39 is provided with a transverse shoulder 41 located at the upper end of the forming member 41.

This finishing operation on the jaw members is such as to do away with the necessity of filing away sharp edges, and does away with such waste. This and previous steps of the method, subsequent to the step of annealing, are carried out without considerable pressure, and do not tend to materially harden the ultimately formed jaw members, so that they remain in the desired soft or pliable condition, yet having some slight degree of springiness.

The final step in the method is illustrated in Fig. 12. A recessed die 42 is provided in the recess with an anvil member 43 having a transverse circular contour which corresponds to the ultimate curvature which it is desired to impart to the side members of the ring guard. A punch 44 is provided with a stamping and forming member 45 having a curvature complementary to the curvature of the anvil 43. In carrying out this step of the 130

method, the guard as completed by the apparatus shown in Figs. 10 and 11 is placed across the anvil 43 evenly and the stamping punch 44 is driven down under sufficient pressure so as to stamp the side members 34, 34^a, shown in Fig. 14, to the desired curvature. The pressure in this step of the method is sufficient to harden the side members 34, 34^a so as to impart the desired springiness there-
10 to. By this stamping step, the sharp edges of the side members are removed so as to do away with the necessity of filing and avoiding the waste of filings. During this step the already formed jaw members 35, 35^a are not
15 directly acted upon, but they are caused to be spread apart more considerably than in the previous step of the method.

Thus the ultimate finger ring guard shown in Figs. 13 and 14 is finally formed, the side
20 members 34, 34^a having the desired spring-
iness and the end jaw members 35, 35^a being
soft and pliable and being thinner in cross-
section than the said side members. In said
25 figures the guard is shown as applied to a
finger ring, and it will be noted that the rel-
atively thin jaw members snugly surround cor-
responding portions of the finger ring, and
that the guard cannot turn upon the ring.
It is a comparatively easy matter to apply the
30 guard to a finger ring, which is performed
by means of any suitable instrument or tool,
which is caused to spread open each said jaw
member so that it may be fitted to the ring,
the jaw members being closed upon the ring,
35 and held thereon against accidental removal.
The metal of the jaw members 35, 35^a being
integral with the metal of the side members
34, 34^a and being relatively thin and of in-
creased width, assists in holding the guard
40 upon the ring, and there being no joints, the
guard is not apt to break at any point there-
of. The jaws of the form described not only
fit the ring snugly at the outside, but at the
inside thereof and provide a considerable area
45 in frictional contact with the ring.

It is obvious that the invention is suscep-
tible to modification without departing from
the spirit of the invention as defined in the
scope of the appended claims.

50 What I claim as new, is:

1. The herein described method of making
finger-ring guards, comprising providing an
elongated loop shaped blank of soft metal
having inwardly curved side members and

outwardly curved end members, all members 55
lying in substantially one plane, subjecting
the end members of the blank to pressure to
thin them relatively to the side members,
bending the end members transversely into
the form of open jaws and to bring the curved 60
side members together in substantially parallel
relation and so that the jaws will extend
away from the side members, subjecting each
end jaw to a finishing action, and subjecting
the side members to sufficient pressure to 65
harden them and to bend them inwardly be-
tween the end jaws, thereby producing the
ultimate ring guard.

2. The herein described method of making
finger-ring guards, comprising providing an 70
elongated loop shaped blank of soft metal
having inwardly curved side members and
outwardly curved end members, all members
lying in substantially one plane, subjecting
the end members of the blank to pressure to 75
thin them relatively to the side members and
to form them in slight curves outward from
such plane, bending the end members trans-
versely into the form of open jaws and to
bring the curved side members together in 80
substantially parallel relation and so that the
jaws will extend away from the side mem-
bers, subjecting each end jaw to a finishing
action, and subjecting the side members to
sufficient pressure to harden them and to 85
bend them inwardly between the end jaws,
thereby producing the ultimate ring guard.

3. The herein described method of making
finger-ring guards, comprising providing an 90
elongated loop shaped blank of soft metal
having inwardly curved side members and
outwardly curved end members, all members
lying in substantially one plane, subjecting
the end members of the blank to pressure to 95
thin them relatively to the side members, an-
nealing the thus treated blank, bending the
end members transversely into the form of
open jaws and to bring the curved side mem-
bers together in substantially parallel rela- 100
tion and so that the jaws will extend away
from the side members, subjecting each end
jaw to a finishing action, and subjecting the
side members to sufficient pressure to harden
them and to bend them inwardly between the
end jaws, thereby producing the ultimate ring 105
guard.

HARRIS LEVIN.
